JAMES FREDRICK CUTHERBERT, OF FERTILITY, ALBERTA, CANADA, ASSIGNOR OF ONE-HALF TO THOMAS P. MANGAN, OF MAUNDERS, ALBERTA, CANADA.

RAILWAY-CROSSING GATE.

Application filed January 26, 1925. Serial No. 4,696.

This invention has relation to certain new and useful improvements in railway crossing gates and controlling means therefor and has for its primary object the provision 5 of a mechanism of this character which is of extremely simple construction and operation with the parts arranged in compact form at the opposite sides of the track and along the rails thereof.

10 This invention has for another object the provision of railway crossing gates and controlling means therefor which will be positive and efficient in its operation and prevent vehicles or pedestrians from crossing the 15 track while a train is passing along the same.

The invention has for a further object the provision of a railway crossing gate and controlling means therefor in which are included hinged platforms at opposite sides 20 of the track to release the gates and thereby permit the same to swing upwardly to operative position at the sides of the track, when the platforms are released by an approaching train on the track and the platform is pressed down by a vehicle or the like 25 passing over the same while the platforms are released, the train again setting or returning the gates to their normal horizontal 30 or inoperative position as the train passes the crossing.

The invention has for a still further object the provision of railway crossing gates and operating means therefor constructed 35 and arranged in such a manner that the gates will be operated only by vehicles passing over the platform at a time when the platforms are released by an approaching train and the gates then again returned to normal 40 horizontal or inoperative position by the train passing the gates after the vehicle has left the platform, so that the vehicle may cross the track and the gates after the train has passed.

45 With the foregoing and other objects in view, as will appear as the description proceeds, the invention consists in the novel construction, combination and arrangement of co-operating elements as hereinafter more specifically set forth, claimed and shown in the accompanying drawings forming a part of the present application and in which:

Fig. 1 is a plan view of the complete invention, with the parts in normal position.

50 Fig. 2 is a vertical section, substantially

on the plane of line 2-2 of Fig. 1, looking in the direction indicated by the arrows.

Fig. 3 is a vertical section, substantially on the plane of line 3-3 of Fig. 1, looking in the direction indicated by the arrows. 60

Fig. 4 is a vertical section at right angles to Figs. 2 and 3 and taken substantially on the plane of line 3-3 of Fig. 1, looking in the direction indicated by the arrows.

Fig. 5 is a detail section, substantially on the plane of line 5-5 of Fig. 4, looking in the direction indicated by the arrows. 65

Fig. 6 is an enlarged detail section, substantially on the plane of 6-6 of Fig. 1, looking in the direction indicated by the arrows. 70

Fig. 7 is a fragmentary detail elevation, 75 showing one of the wheel actuated platform releasing members and the mounting of the same.

Referring more in detail to the drawings in which similar reference characters designate corresponding parts throughout the several views, it is to be noted that a gate 10 is hingedly mounted along its outer longitudinal edge in the gate supporting frame 11, at either side of the track 12 and outwardly of the track rails 12^a. The gates 10 are arranged to spring downwardly toward the track 12, as shown clearly in Fig. 2 of 80 the drawings. A platform 13 is also hingedly mounted in a platform frame 14, outwardly of each gate 10. The gate 10 and platform 13 will be described more in detail, 85 as the description proceeds. 90

It will be readily seen from the drawings, particularly Figs. 2 and 3, that the gate frames 11 and platform frames 14 are countersunk in the surface of the road crossing track, so that when the gates 10 and platforms 13 are in normal position, they are flush with the surface of the road. This will permit the vehicles to move along the road and over the track 12 without injury to the parts of the invention on either side of the track 12. On either side of the track 12, the gate 10 is held in its normal or horizontal position within the frame 11, by latch members 15, which are pivoted on the pivot members 16, within the frame 11 and extended over the edge of the gate 10, as clearly shown in Fig. 3. The latch members 15 are resiliently retained in normal or operative position by appropriate springs 105 connected therewith and with the frame 110 17

11. Releasing cables 18 are connected with the latch members 15 and with the lower ends of bell crank levers 19 which are mounted intermediate their arms on pivot members 20 provided for this purpose on the supporting brackets 21, beneath the platform 13, as shown clearly in Fig. 3. The bell crank levers 19 are arranged in such a manner that their curved arms engage the under face of the platform 13, near the free edge thereof opposite the hinged edge of the platform 13. Expansion springs 22 are arranged beneath the platform 13 to resiliently retain the latter in its normal horizontal position. A latch bolt 23 is also provided for the platform 13 and when in operative position, engages beneath the depending member 24 on the last mentioned free edge of the platform 13, to prevent downward movement of the platform 13 on its hinge 25. It is apparent that when the latch bolt 23 is withdrawn to inoperative position, the weight of the vehicle or a pedestrian on the platform 13 will serve to press the latter on downwardly on its hinge 25 and against the action of the springs 22, thereby operating the bell crank levers 19 on their pivots 20 and pulling on the cables 18 to actuate the latch members 15 and swing the latter on their pivots 16 to inoperative position, thereby releasing the gate 10 and permitting the gate 10 to be swung upwardly on its hinge 26, under the influence of the spring 27 connected by one end with the gate frame 11, while the other end thereof is connected with an arm 28 extended from the hinged edge of the gate 10, as shown in Fig. 2. A rod 29 is connected with the arm 28 and extended loosely through an opening 30 provided therefor transversely in the web portion of the track rail 12^a, as shown in detail in Fig. 5. The rod 29 is connected with the inner end of a plate 31 and is pivotally connected with the opposed inner end of a second plate 32, by a link 33 carried by said plate 32 and pivoted to the rod 29. The plates 31 and 32 diverge toward their other ends and are mounted on the supporting bolt 34 extended through the web of the rail 12^a and through elongated longitudinal slots 35 in the outer ends of the plates 31 and 32, as shown clearly in the drawings. The plates 31 and 32 have their main portions offset and extended upwardly to a plane nearly parallel with the upper edge of tread portion of the rail 12^a, so that the flanges of the car wheels passing along the rail 12^a will force the plates 31 and 32 toward the rail 12^a, forcing the rod 29 outwardly to return the gate 10 to its horizontal or inoperative position, against the tension of the spring 27, and permit the gate 10 to be automatically locked in its horizontal inoperative position by the latch members 15, as the train 65 passes the crossing.

The latch bolt 23 works through the bolt casing 36 carried by the platform frame 14 and a pair of cables 37 are extended from the latch bolts 23 which may be any conventional form of spring latch appropriate for this purpose. The cables 37 extend toward the track rail 12^a, then pass around guide pulleys 38 and diverge so as to extend in opposite directions along the outer face of the track rail 12^a. The ends of the cables 37 are connected to the platform releasing levers 39 which are positioned on the side of the track rails 12^a and mounted on suitable pivot members 40 so that the free ends 41 of the levers 39 project above the track rail 12^a to cause operation of the proper levers 39 and thereby release the platform 13. The levers 39 are resiliently retained in normal position by springs 42 connected therewith and with the track rail 12^a, as shown in detail in Fig. 7. It will be apparent from the drawings, particularly Fig. 7, that the operation of the levers 39 by trains passing in one direction over the track rails 12^a will result in releasing of the platform 13 by the levers 39 at one side of the crossing, while the operation of the levers at the other side will have no effect upon the latch bolt 23. This will be reversed when trains are passing over the rails 12^a from the other direction and in this case, the first mentioned levers 39 will operate without having any effect upon the latch lever 23. By referring to Fig. 6, it will be seen that the latch bolt 23 for each platform 13 is resiliently retained in operative position by the spring 43 within the casing 36 of the latch bolt 23 and which casing 36 has a removable end or head 44. This is the preferred form of latch bolt employed but such details may be varied, as desired.

It is believed the complete construction and operation of the railway crossing gates and operating means therefor may now be apparent to parties familiar with this art, from the foregoing paragraphs, taken in connection with the accompanying drawings, without further detail description. It may be briefly stated, however, that the platform 13 and gate 10 at each side of the crossing are normally in horizontal position so that vehicles and pedestrians may cross the track without difficulty, as long as there is no danger from approaching trains. While the gates 10 are located adjacent the track, the platforms 13 should be located some distance from the crossing as will be evident. When a train is approaching from either direction on the track, the platform releasing levers 41, which are also some distance from the crossing will be operated by the wheels of the train to withdraw the latch bolt 23 and thereby release the platform 13, so that the weight of a vehicle or pedestrian upon the platform will press the same down- 130

wardly against the action of the springs 22 and thereby operate the bell crank lever 19 under the platform, thus actuating the latch members 15 for the gates 10 at the side of the track from which the vehicle or pedestrian is approaching the crossing. The spring 27 for the gate 10 will immediately act to swing the gate 10 upwardly in front of the vehicle or pedestrian and thereby prevent crossing of the track. As the train reaches the crossing, the wheels thereof will act upon the plates 31 and 32 to return the gate 10 to its normal horizontal or inoperative position, where it will be again caught by the latch member 15, thereby leaving the gate 10 in position for the vehicle or pedestrian to cross the track immediately after passing of the train. It is to be understood that the vehicle or pedestrian moves off of the platform 13 toward the gate 10 immediately after operation of the platform 13, so as to permit the latch members 15 to resume their operative positions for automatically catching and holding the gate 10 when the latter is returned to its normal horizontal or inoperative position. It is also apparent that the gate 10 need not be operated unless a vehicle or pedestrian is crossing the platform at the time a train is about to pass the crossing.

While the preferred embodiment of the invention has been disclosed, it is to be understood that minor changes in the details of construction, combination and arrangement of co-operating elements may be resorted to within the scope of what is claimed, without departing from the spirit of the invention.

What I claim as new is:

1. A railway crossing gate and operating means therefor including a gate adjacent the track; a platform associated with said gate; latch means for said gate; latch means for said platform; means carried by the

track for releasing the platform as a train approaches the crossing; means for releasing the latch means for the gate when the platform is pressed downwardly by a weight upon the same after releasing of the latch means for the platform; and means operable by the train for returning the gate to inoperative position as the train passes over the crossing. 45

2. A railway crossing gate and operating means therefor including the combination with said track rails; of hinged gates mounted near the rails and outwardly of the sides of the track; platforms hingedly mounted outwardly of the gates; latch means for retaining the gates in normal horizontal unoperated position; means for resiliently supporting the platforms in normal horizontal unoperated position; latch bolts extending beneath said platforms to prevent downward swinging movement of the platform; means mounted on the rails of the track at a suitable distance from the crossing to withdraw said latch bolts as a train approaches the crossing; means operable by the platform when pressed down after withdrawal of the latch bolts to release said gates; means to automatically swing the gate upwardly when released; means at the crossing and operable by the train to return the gates to horizontal unoperated position as the train passes the crossing; the latch bolt withdrawing means at either side of the crossing being arranged to withdraw the bolts when operated in one direction only, thereby making the said means at either side of the crossing operable according to the direction of travel 75 of the train on the track rails; a counter-sunk frame for each gate; and a counter-sunk frame for each platform. 80

In testimony whereof, I affix my signature.

JAMES CUTHBERT.
